UNITED STATES PATENT OFFICE.

ROLAND CAVICCHI, OF QUINCY, MASSACHUSETTS.

AUTOMOBILE-LOCK.

1,109,961.

Specification of Letters Patent.

Patented Sept. 8, 1914.

Application filed June 28, 1913. Serial No. 776,221.

To all whom it may concern:

Be it known that I, ROLAND CAVICCHI, a citizen of the United States, residing at Quincy, county of Norfolk, State of Massachusetts, have invented an Improvement in Automobile-Locks, of which the following description, in connection with the accompanying drawing, is a specification, like characters on the drawing representing like parts.

My invention has reference to locking devices by which a controlling lever may be locked in one position and is particularly adapted to be applied to automobiles for holding a controlling lever in neutral or inoperative position.

One object is to provide a locking device that may be readily applied to existing automobiles.

Another object is to provide a locking device which when applied to an automobile may be placed on the machine in such a position that it can be conveniently reached from the seat, and which need not be in any way connected to the H gate or other lever guiding devices.

Other objects will appear from the following specification in which my invention will be fully disclosed and the novel features 30 will be particularly pointed out in the claims.

In the drawing: Figure 1 is a view partly in section of my improved device; Fig. 2 is a plan view of the same; Fig. 3 is a sectional view on the line 3—3 Fig. 1; and Fig. 4 is a view on the line 4—4 Fig. 1.

Referring to the drawing which illustrates one embodiment of my invention 1 indicates a controlling lever of an automobile to which my device is applied and 2 indicates a part of the frame to which the lock-case 3 is permanently secured.

A movable arm 4 is preferably pivotally connected to the lever 1 as by means of a strap 5 and rivet 6, so that it may swing up to locking position as shown in full lines in Fig. 1 or down to inoperative position as shown in dotted lines. The keeper 7 is shaped to receive and interlock with the movable arm 4. I have shown this keeper as made integral with the lock-case but it is sometimes desirable to make it as a separate member. In the construction shown in the drawing the arm 4 is provided with 55 a tongue 8 which fits in a corresponding recess 9 in the keeper 7 and a rib 10 formed in

the keeper fits in a transverse recess 11 in the tongue 8. Thus when the parts are in interlocking position as shown in full lines in Fig. 1, movement of the arm in a longitudinal direction is prevented by the engagement of the rib 10 in the recess 11.

To lock the tongue 8 in the recess 9 of the keeper and thereby prevent movement of the arm in a downward direction, I provide 60 a locking member 12 having a spring pressed locking pin 13 in its forward end, the forward movement of this pin being limited by a shoulder as shown at 14. A recess 15 is provided preferably in the end of the tongue 65 8 to receive the pin 13 and the tongue is beveled to press the pin back into the locking member as it moves into the recess in the keeper. The locking member 12 is 70 75 slideable in the keeper and may be controlled by any suitable mechanism. In the construction shown a tension spring 16 is secured to the locking member 12 and to the opposite side of the lock-case. An upwardly extending arm 17 on the locking member is engaged by 75 two rotatable disks 18 and 19 and thereby held in forward position against the action of the spring. The lower disk 18 is secured to the stem 20 and is provided with a pin 21 which is adapted to engage a pin 22 in the 80 disk 19 which latter disk is rotatably supported within the lock-case in any suitable manner. The head of the stem 20 is knurled as shown at 23 and a scale is provided as indicated at 24 as is usual in combination 85 locks. The disk 18 is provided with a notch 25 as clearly shown in Fig. 4, one side of the notch being shaped as a cam to force the locking member into its forward position. The other disk 19 is provided with a notch 90 95 26 as shown in dotted lines in Fig. 4. As will be seen, the stem 20 may be rotated in one direction the pin 21 engaging the pin 22 and thereby rotating the disk 19 until the notch 26 is opposite the arm 17 100 of the locking member. Then the stem may be rotated in the opposite direction until the notch of the disk 18 is in a position opposite the arm 17 of the locking member and the spring 16 will operate to draw the 105 locking member backward releasing the movable member 4.

I prefer to provide means to hold the movable arm in its operative position and in its inoperative position relative to the lever and 110 in the embodiment of my invention illustrated I have accordingly provided a yield-

able detent 27 which engages the notches 28 and 29 in the ends of the strap 5.

The operation of the device is as follows: When it is desired to apply the lock the lever is moved to the position in which it is adapted to be locked and the movable arm 4 is raised to engage the keeper 7. The locking pin 13 is pressed backwardly against its spring by the beveled end face of the arm 4 until the recess in the end of the arm comes 10 opposite the locking pin whereupon the pin springs into said recess. When it is desired to unlock the lever the disks are rotated by means of the stem 20 as above explained, to bring both notches opposite the upwardly 15 extending arm 17 of the locking member and the locking member is withdrawn by the spring 16. The arm 4 may then be pushed down and the lever is free to be operated. The stem may then be turned to force the 20 locking member into its forward position and the parts are in position to be readily locked again when desired.

Having described my invention, what I claim as new and desire to secure by Letters 25 Patent is:—

1. A device of the class described comprising a movable arm, a keeper shaped to receive said arm and a locking member movable relative to said keeper toward and from said arm and comprising a body member and a spring-pressed locking pin carried 30 by said locking member and yieldable relative thereto to permit the insertion of the arm in the keeper but normally positioned to retain said arm when inserted.

2. A locking device comprising a keeper, an arm movable to engage the keeper and an arm movable to engage the keeper and interlock therewith in such a manner as to

prevent relative movement in one direction, 40 a locking member movable relative to the keeper and comprising a body member and a spring-pressed locking pin movable relative to said body member to engage the movable arm and retain it in interlocking engagement with the keeper and means for controlling the locking member.

3. A device of the class described comprising an arm adapted to be connected to a lever, a keeper shaped to receive the arm, 50 a locking member movable relative to said keeper and toward and from said arm when said arm is in position in said keeper, and comprising a body member and a spring-pressed locking pin carried by said body 55 member yieldable to permit insertion of the arm in the keeper while the body member is in position toward said arm, but positioned to retain said arm when inserted, and means controlling said locking member. 60

4. A device of the class described comprising an arm adapted to be pivotally connected to a lever in such a manner that it is capable of movement to operative and inoperative positions, a keeper shaped to 65 receive said arm and interlock therewith to prevent longitudinal or lateral movement of said arm, means to lock said arm in said keeper comprising a slidible member and a spring-pressed pin carried by said slidible 70 member and movable relative thereto.

In testimony whereof, I have signed my name to this specification, in the presence of two subscribing witnesses.

ROLAND CAVICCHI.
